(57) **CLAIM**

The ornamental design for balance scale, as shown and described.

DESCRIPTION

FIG. 1 is a side perspective view of a balance scale incorporating the scale in accordance with the new design;

FIG. 2 is a side perspective view thereof;

FIG. 3 is a top plan view thereof;

FIG. 4 is a left side elevational view thereof;

FIG. 5 is a right side elevational view thereof;

FIG. 6 is a front elevational view thereof;

FIG. 7 is a rear elevational view thereof;

FIG. 8 is a bottom plan view thereof; and,

FIG. 9 is a left side partly cross elevational view thereof.

The broken line showing is for illustrative purposes only and forms no part of the claimed design.
